FUEL PUMP DRIVE

Filed March 12, 1928

UNITED STATES PATENT OFFICE

HARRY S. GOLDEN, OF FLINT, MICHIGAN, ASSIGNOR TO GENERAL MOTORS CORPORATION, OF DETROIT, MICHIGAN, A CORPORATION OF DELAWARE

FUEL-PUMP DRIVE

Application filed March 12, 1928. Serial No. 261,145.

This invention relates to a power transmitting means intended more particularly for operating a fuel pump of an internal combustion engine.

5 The invention has for its object the provision for power transmitting means permitting a driven mechanism to be conveniently located at a distance from the source of power which is to operate its movable parts. More 10 specifically, the invention provides for the convenient operation of a fuel pump when positioned on that side of the engine remote from the cam shaft which is used to operate it.

Another object is to locate the fuel pump 15 in a position removed from the generator and starting motor to thereby prevent the possibility of the ignition of any fuel which might leak from the pump by sparks from the generator or motor.

20 Another object of the invention is to provide for the location of the fuel pump on that side of the engine which is comparatively free from engine accessories.

The objects of the invention also include 25 simplicity in construction and economy in manufacture. Other objects and advantages will be understood from the following specification and the accompanying drawing.

In the drawing:

30 Figure 1 is a transverse section through an internal combustion engine embodying an improvement in accordance with this invention; and

Figure 2 is a bottom plan view of a detail 35 used with the invention.

Referring by reference characters to the drawing, numeral 3 is used to designate an engine block mounted upon a crankcase 5. Numeral 7 is a pan secured to the crankcase 40 by fastening means 9. Numeral 11 is the conventional crankshaft mounted in a half bearing 13 and a removable cap 15, as usual. The camshaft 17 has a cam 19 added thereto for operating the fuel pump. At 21 is an air cleaner of any preferred form mounted over an opening 23 in the crankcase.

Secured to the side wall 25 of the crankcase by any suitable fastening means is a fuel pump designated as an entirety by numeral 50 27. The fuel pump has near its base and on

one side an opening 29 registering with an opening 31 in the wall 25 whereby the operating means for the pump may be accommodated.

The invention is not concerned with the 55 details of the pump, per se. The pump is, however, of the variable stroke type having an operating plunger 33 which is at times pulled down to effect a suction stroke. Pivoted at 35 adjacent the opening is a bell 60 crank lever having a horizontal arm 37 projecting outwardly and normally pressed upwardly by a coil spring 39, a cap 41 secured to the bottom of the pump housing and forming a lower abutment for the spring. Articulated links 43 and 45 pivotally connect the plunger 33 with the end of horizontal arm 37. These links are constructed to approach, but not to reach, alignment and when lever 37 is rotated clockwise it operates to pull 70 plunger rod 33 through the instrumentality of links 43 and 45, and create a suction stroke in the variable volume chamber of the pump. A spring 47, positioned as shown in the drawing, may create a compression stroke, but being resilient operates against the fluid pressure in the pump chamber. It therefore produces such a stroke only when the resistance of the fluid in the chamber permits. If the 75 chamber is full and the communication with the carburetor affords no relief, spring 47 is unable to force the fluid out of the chamber and through the usual outlet valve. The pump valves are of any preferred type and access to these valves is had by plugs 51. The 80 action of the pump is well known and need not be further described.

Beneath the top wall of the crankcase is secured a bracket 51 by fastening means 53. This bracket has bearings 55 and 57 in alignment for slidably carrying a rod 59. The rod engages at one end a vertical arm 61 formed on the bell crank and at its other end engages cam 19. As the camshaft rotates the rod 59 is reciprocated to the right as shown 90 in Figure 1. The spring 39 operates to push against the bell crank and hold rod 59 at all times against the cam. When the spring 39 is moving bell crank upwardly, the spring 47 may execute a discharge stroke, in which 100

case the links 43 and 45 do not collapse. If, however, the pressure in the pump chamber balances the pressure of spring 47, no discharge stroke occurs and the links 43 and 45 collapse in a manner which is well known in this type of pump.

The arrangement described permits the location of the pump on that side of the engine which, in the case of the engine for which it has been especially designed, is comparatively free from engine accessories. It also permits the pump to be located away from the danger of sparks from the motor or generator. It provides a simple and economical arrangement for actuating the pump by the simple provision of a reciprocating rod extending transversely of the crankcase and above the crankshaft.

I claim:

20 1. In combination, an internal combustion engine, an accessory having a driven part, the accessory located at one side of the engine, a source of power adjacent the other side of the engine, means mounted for axial reciprocation transversely of said engine and terminally engaging said power source and driven part.

25 2. In combination, an internal combustion engine, a longitudinally extending camshaft adjacent one side of said engine, a fuel pump adjacent the other side of said engine, said pump having means to operate the same, a rod mounted for movement along its longitudinal axis transversely of said engine, engaging said camshaft and movably engaging the pump operating means.

30 3. In combination, an internal combustion engine, a crankcase therefor, a crankshaft positioned medially therein, a parallel cam-shaft adjacent one side thereof, a fuel pump adjacent the other side of said engine, said pump having an actuating lever, an axially reciprocating rod positioned transversely of the engine and movably engaging a cam on the camshaft and an arm on the lever.

35 4. In combination, an internal combustion engine having a crankshaft and a parallel camshaft, a bracket carried by said engine having aligned bearings, a rod reciprocably mounted in said bearings within the crankcase, transversely of the engine, and terminally engaging the cam, a fuel pump on the side of said engine remote from the cam-shaft, said pump having a movable operating part, and said reciprocating rod engaging said operating part.

40 5. The invention defined by claim 4, together with a spring in said pump engaging said operating part and effective to hold the reciprocating rod in contact with the cam on the camshaft.

In testimony whereof I affix my signature.

HARRY S. GOLDEN.
